Lessler; Gary Lipson

(57) **CLAIM**

The ornamental design for a combination artificial Christmas tree and musical speaker, as shown and described.

DESCRIPTION

FIG. 1 is a front view of a combination artificial Christmas tree and musical speaker showing my new design, the tree shown in broken lines for illustrative purposes only and forms no part of the claimed design;

FIG. 2 is a rear view thereof;

FIG. 3 is a left side view thereof;

FIG. 4 is a right side view thereof;

FIG. 5 is a top view thereof; and,

FIG. 6 is a bottom view thereof.
